[57] **CLAIM**

The ornamental design for the bottom section of an ink bottle, as shown and described.

DESCRIPTION

FIG. 1 is a left side elevation view of my new bottom section of an ink bottle;

FIG. 2 is a front elevation view thereof;

FIG. 3 is a bottom view thereof;

FIG. 4 is a right side elevation view thereof; and,

FIG. 5 is a rear elevation view thereof.

The top view is ordinarily not visible as it is inside of the bottle. The broken line showing of the remainder of the bottle is for illustrative purposes only and forms no part of the claimed design. The dashed lines in FIGS. 2, 3 and 5 show the boundaries of the claimed design and form no part thereof.
